OPTOMETRIC MIRROR

Martin O. Weisbrod, Chicago, Ill.

Application April 16, 1949, Serial No. 2,063

Term of patent 14 years

(CL. D33—9)

To all whom it may concern:

Be it known that I, Martin O. Weisbrod, a citizen of the United States, residing at Chicago, in the county of Cook and State of Illinois, have invented a new, original, and ornamental Design for an Optometric Mirror, of which the following is a specification, reference being had to the accompanying drawing, forming a part thereof.

Fig. 1 is a front view of the optometric mirror embodying the new design;

Fig. 2 is a top plan view; and

Fig. 3 is a side view.

The side of the optometric mirror not shown is identical to the side shown in Fig. 3.

I claim:

The ornamental design for an optometric mirror, substantially as shown and described.

MARTIN O. WEISBROD.
